(57) **CLAIM**

The ornamental design for a table, as shown and described.

DESCRIPTION

FIG. 1 is a perspective view of the table of the present invention;

FIG. 2 is a top view of the table of FIG. 1;

FIG. 3 is a bottom view of the table of FIG. 1;

FIG. 4 is a front view of the table of FIG. 1; and,

FIG. 5 is a side view of the table of FIG. 1.

The table of the present invention is symmetrical and the left and right sides are identical as are the front and rear views.
